UNITED STATES PATENT OFFICE.

WILLIAM N. STACEY, OF SPRINGFIELD, MASSACHUSETTS.

DESIGN FOR A LUNCH-ROOM CHAIR.

48,402.

Specification for Design.

Patented Jan. 4, 1916.

Application filed September 27, 1915. Serial No. 52,964. Term of patent 14 years.

To all whom it may concern:

Be it known that I, WILLIAM N. STACEY, a citizen of the United States of America, residing at Springfield, in the county of Hampden and State of Massachusetts, have invented a new, original, and ornamental Design for Lunch-Room Chairs, of which the following is a specification, reference being had to the accompanying drawings, forming part thereof.

Figure 1 is a side elevational view; Fig. 2 is a plan view; and Fig. 3 is a front elevational view, showing my new design.

I claim:

The ornamental design for a lunchroom chair, as shown.

WILLIAM N. STACEY.
